VELOCIPED FORK

Bert J. Anderson, Hammond, Ind.

Application December 12, 1935, Serial No. 54,116

3 Claims. (Cl. 280—279)

This invention relates to an improved fork for a velocipede and has for one of its principal objects the provision of means for economically producing a sturdy and dependable article from a single stamping.

Another and further important object of the invention resides in the provision of means for providing shaft bearings at the lower ends of the fork.

Still another and further important object of advantage of the improved fork of the invention resides in the provision of means for securing a handle bar to the upper end of the steering post.

Additional objects of importance and advantage will be apparent from the disclosures made in the following detailed description, reference being had to the accompanying drawing, wherein

Fig. 1 is a front elevational view of a velocipede fork which embodies the preferred form of the invention.

Fig. 2 is a side elevational view thereof.

Fig. 3 is a section taken on line 3—3 of Fig. 2.

Fig. 4 is a top plan view of the embodiment shown in Fig. 1.

Fig. 5 is a section taken on line 5—5 of Fig. 1.

Fig. 6 is an elevational view of the joined ends of the fork post and a handle bar post, parts thereof being broken away, and

Fig. 7 is a sectional view taken on line 7—7 of Fig. 6.

As shown in the drawing:

The reference numeral 10 indicates in general the post or stem portion of a sheet metal fork. In the preferred embodiment of the invention the edges 12 of the post 10, which are joined at the front thereof, are interlocking as is best shown in Fig. 1. It will be apparent that departures covering a wide range and using various conventional forms of interlocking edges may be used in the forming of the post. The view in Fig. 1 being used merely to illustrate the preferred construction.

Formed in the upper end of the improved fork, preferably directly opposite the joined edges 12 is a vertical tongue 14 which is adapted to engage a portion of a handle bar 13. In the preferred construction of the improved fork, the upper end of the tongue 14 terminates flush with the end of the post. In the present construction it will be noted that the edges 15 of the openings 16 on each side of the tongue 14 are adapted to contact portions of the handle bar and thus are utilized in transferring rotative force from said handle bar to the fork.

Formed in opposed sides of the tubular post 10,

slightly below the level of the base of the tongue, are bolt receiving openings 18 which are adapted to receive a bolt 19 to prevent longitudinal movement of a handle bar positioned on the post.

Formed at the base of the tubular post 10 is 5 a shoulder 20 which serves as a thrust bearing when the fork is assembled with a velocipede frame.

Extending downwardly from opposed sides of the shoulder 20 is a pair of prongs 22 which preferably are segmental in cross section, as is best shown in Fig. 5. It will be noted that each prong 22 comprises a segment of considerable width to a point adjacent each lower end thereof. This construction allows a relatively light gauge metal 15 to be used in the construction of the fork, but still produces a strong and rugged article.

The lower end of each prong 22 is turned outwardly and curled to produce a bearing 24. The edges 26 of the bearing 24 are preferably joined 20 at the bottom thereof. The bearings 24 are in alignment and are adapted to support a pedal or crank shaft. The upper surface of each bearing 24 is preferably flat, as is best shown in Fig. 2, to provide a stronger and more rigid construction 25 and to also form a support for a fender.

Extending diagonally from the middle of the top surface of each bearing 24 to the prong 22 is a rib 26a which adds greatly to the strength 30 and appearance of the structure.

It will be apparent from the foregoing that herein is provided a sturdy and rugged fork and steering post which may be economically constructed of a single stamping.

It will be further apparent that because of the wide bearing surfaces afforded for the pedal shaft the device is exceptionally long lived and moreover, the pedal shaft is not soon scored or grooved.

I am aware that many changes may be made 40 and numerous details of construction varied throughout a wide range without departing from the principles of this invention and I, therefore, do not purpose limiting the patent granted hereon otherwise than as necessitated by the prior art. 45

I claim as my invention:

1. A fork for a velocipede comprising, a single stamping having a tubular upper portion and a bifurcated lower portion, means for rotatably securing a shaft to said bifurcated lower portion, 50 said means comprising each end of said lower portion being turned outwardly and portions of said outwardly turned ends being adapted to be crimped about a shaft, and a tongue formed of a part of said tubular upper portion, said tongue 55

comprising means for attaching operating means to the fork.

2. A fork for a velocipede comprising, a stamping having an apertured tubular upper portion and a bifurcated lower portion, means for rotatably securing a shaft to said bifurcated lower portion, said securing means providing a tubular bearing surface having a width of at least twice the thickness of the metal of the stamping and
- 5 10 a tongue providing means for attaching an operating handle thereto, said tongue being formed of a part of said tubular upper portion.
- 10 15 3. A fork for a velocipede comprising, a stamp-

ing having an apertured tubular upper portion and a bifurcated lower portion, the edges of said tubular upper portion being interlocked, means for rotatably securing a wheel to said bifurcated lower portion, said means comprising bearings 5 formed of the outwardly projecting ends of said bifurcated lower portion, said outwardly projecting ends being curled to form substantially tubular bearing members, and a tongue formed of a part of said tubular upper portion, said tongue 10 providing means for securing an operating member to the upper portion of said fork.
